ROTARY SHEET TRANSFER MECHANISM

Henri E. Peyrebrune, Elmwood Park, Ill., assignor to Miehle Printing Press & Manufacturing Company, Chicago, Ill., a corporation of Illinois

Application February 1, 1937, Serial No. 123,344

14 Claims. (Cl. 271—56)

The invention relates to sheet transfer mechanism and has reference more particularly to an improved rotary sheet transfer means which will operate to transfer a sheet only when the sheet is properly delivered thereto and accurately registered throughout its leading edge.

The improvements of the invention have particular application to mechanism for feeding sheets as shown in Patent No. 1,991,003 granted to Burt D. Stevens on February 12, 1935 wherein the sheets to be printed are engaged after having been brought to register while at rest on a sheet support and are subsequently accelerated to the speed of a moving printing member such as an impression cylinder and transferred thereto so that at the time when a sheet is grasped by the sheet holding means of the printing member it will have attained the surface speed of said member. To make possible the registration of a sheet while at rest the transfer means of said patent is decelerated prior to being brought to rest and the sheets are delivered to the transfer means while the same is decelerating. More particularly, said sheets are delivered to the transfer means when the velocity of said means is approximately the same as that of the sheet so that the sheets are gradually brought to rest for registering purposes and in a manner preventing jarring of the sheet.

However, in the event a sheet is not delivered to said transfer means the same will operate as usual. This is very undesirable for a number of reasons and it is also undesirable for the printing couple to operate in the absence of a sheet. Also actuation of the transfer means as heretofore constructed would take place although a sheet may not be properly registered, or if a part only of the leading edge of the sheet were properly registered, which would happen occasionally notwithstanding the efficiency with which the mechanism operated to slow down a moving sheet and bring the same to rest for registering purposes.

The present invention is an improvement in rotary sheet transfer means and accordingly the improved structure overcomes the above objectionable features. More particularly the invention resides in the provision of clutch means which will permit the transfer mechanism to remain at rest unless a sheet is delivered thereto and is properly registered throughout its leading edge. Thus rotary sheet transfer means of the type described when equipped with the improvements of the invention will not operate unless certain necessary conditions are fulfilled, that is, feeding of a sheet thereto followed by accurate regis-

tration of the entire leading edge of the same. The improvements of the present invention further reside in the provision of tripping means for the printing couple which will have automatic operation in the event the transfer means remains at rest to trip either the plate or impression cylinder, thereby preventing a printing operation. As a result, the present invention will insure delivery of all sheets in timed relation with other operating parts of the press and will insure perfect registration of each and every sheet printed by the printing couple associated therewith.

A more specific object of the invention is to provide impression cylinder tripping means in combination with rotary transfer mechanism having accelerating motion for transferring a sheet from a position of rest to a printing cylinder, followed by uniform motion, and finally a decelerating motion for slowing down the next sheet prior to bringing the same to rest for registering purposes.

With these and various other objects in view, the invention may consist of certain novel features of construction and operation, as will be more fully described and particularly pointed out in the specification, drawings and claims appended hereto.

In the drawings which illustrate an embodiment of the invention and wherein like reference characters are used to designate like parts—

Figure 1 is an elevational view showing the improvements of the invention applied to rotary sheet transfer means adapted to transfer sheets to a rotating impression cylinder;

Figure 2 is a view similar to Figure 1 showing the position the parts assume when the clutch of the invention has been tripped, preventing operation of the rotary transfer means; and

Figure 3 is an elevational view of the mechanism shown in Figure 1, the registering table being shown in section to illustrate the means for detecting the presence or absence of a sheet.

Referring to the drawings, 10 designates the impression cylinder and 11 the blanket or plate cylinder of the printing press chosen for illustrating the present invention. The blanket or plate cylinder 11 is suitably journaled by means not shown, while the impression cylinder 10 is carried by shaft 13 journaled in the side frames of the press. These cylinders in the type of press shown are continuously rotating and are geared together in the usual manner. Sheets are transferred from the registering table 14 to the impression cylinder 10 by the transfer mechanism designated in its entirety by 15, which feeds a

sheet to the usual grippers 16 carried by the cylinder. The sheet while being carried around the cylinder 10 will receive its impression as it passes between said cylinder and the plate cylinder 11 which will be inked in any well known manner.

The transfer mechanism 15 comprises arms 17 fixed to the transfer shaft 18 journalled in frames 19 in the press and which carry sheet engaging grippers 20 pivotally mounted at 21. Said grippers may be operated in any well known manner to open and close. Arms 17 are joined by a member 22 carrying sheet retarding and aligning fingers 23 which extend into the path of the fed sheet and operate to slow down the sheet for registering purposes. Obviously, any desired number of grippers 20 and cooperating parts may be arranged on the transfer shaft 18, depending on the width of the sheets to be handled. In order to provide clearance for the grippers 20 and sheet aligning fingers 23 the registering table is recessed so that a plurality of raised portions 25 are formed which will function to support the leading portion of the sheet on the table across its entire width.

The transfer mechanism above described has rotation from a position of rest, as shown in Figure 1, during which the sheet is registered by the guides 26 provided adjacent the front edge of the registering table 14 and which have pivotal movement on axis 27 so that the guides may move forward out of the path of the sheet after their registering function is completed. The registered sheet is engaged by the grippers 20 and accelerated motion is imparted to the transfer mechanism so that when the sheet is presented to the cylinder grippers it will have reached the surface speed of said cylinder. The transfer mechanism will continue to rotate uniformly for part of a revolution and will then have decelerating motion for the purpose of slowing down a sheet and bringing the same to rest gradually for registering purposes. For a more complete description of the transfer mechanism, its manner of operation, and the driving means therefor, reference is made to the Stevens Patent No. 1,991,003 previously mentioned.

The improvements of the invention reside in the provision of sheet detecting means that will indicate the absence of a sheet on the registering table 14 at the time the transfer mechanism is at rest and which will further indicate an improperly registered sheet. The structure for accomplishing the above function consists of suction means which are incorporated in the registering table 14 at the forward edge thereof, the same residing in a plurality of openings 24 in the upper surface of the raised portions 25 which connect with the suction tubes 28 leading to the disc valve 29. The suction openings 24 are located in the registering table along the entire width of the registering guides 26 associated with said table so that the same will detect not only the absence of a sheet but also an improperly registered sheet, that is, one in which the leading edge is not in contact with the registering guides throughout its entire width. The suction tube 28 has connection with a disc valve 29, Figure 1, suitably fixed to cam shaft 30 carrying the cam 31. The said disc valve in turn connects with the main suction supply tube 32 and at the proper time in the operation of the press said valve will connect the supply tube 32 with tube 28 leading to the suction openings 24 in the registering table. Also connecting with tube 28 is tube 33 leading to mem-

ber 34 suitably fixed to one of the side frames 19 of the press. Said member is provided with a suction chamber having piston 35 to which is fixed a piston rod 36 projecting above the member forming a projection 37. The coil spring 38 yieldingly forces said piston in a downward direction against the base of member 34.

The operation of the detecting means above described will occur in synchronism with the operations of the printing press since the cam shaft 30, carrying disc valve 29, is suitably geared so as to rotate continuously and in timed relation with the impression cylinder. When a sheet is registered by said registering guides 26 the same will be caused to overlie the suction openings 24 during the time the transfer mechanism is at rest and during this time the disc valve 29 will connect said suction openings with the main suction supply 32. Since said suction openings will be closed by said sheet air will be exhausted from the chamber of member 34 and the piston 35 will be elevated against the tension of spring 38, causing projection 37 to extend above said member. Advantage is taken of the presence or absence of said projection 37 to control the actuation of clutch means applied to the transfer mechanism, which structure will now be described.

As shown in Figure 1, the transfer shaft 18 has suitably secured thereto a yoke member 40 having spaced arms 41 which slidably mount a trip latch 42 so as to permit reciprocation thereof. The sides of said latch are recessed and the same is retained within said yoke by screws 43 threaded in the arms 41 and which extend into said recesses. The lower end of said trip latch is reduced in size forming a rod 44 which extends into an opening provided therefor in the transfer shaft. Encircling said rod and having contact at one end with the trip latch and at its other end with the shaft is a coil spring 45 which yieldingly forces said trip latch in an upward direction.

The transfer mechanism is rotated by a driving disc 46, best shown in Figure 3, which is journalled by said transfer shaft 18 for rotation independently thereof. Said driving disc is provided with an annular flange 47 partially shown in section in Figure 1 and which is provided with an opening through which the trip latch 42 is adapted to extend to thereby operatively connect the driving disc and the transfer shaft 18, causing rotation of the transfer shaft to take place in accordance with the driving impulses transmitted thereto by the disc 46.

Actuation of the trip latch 42 is controlled by a trip pin 50 adapted to engage the bifurcated upper end of said latch. Arm 51 of the bell crank lever 52 carries said trip pin 50, the said lever being supported for pivotal movement by shaft 53 and having portion 54 formed on the lower end thereof. Said portion is provided with a shoulder adapted to contact projection 37, the said bell crank lever being yieldingly biased in a direction to cause movement of the portion toward projection 37 by coil spring 55 fixed to the bell crank lever at one end and secured to the side frame of the press at its other end. The lower end of said bell crank lever carries a roller 56 which is adapted to have engagement with the cam 57 fixed to and rotating with shaft 13 carrying the impression cylinder.

In operation of the structure above described it will be understood that the bell crank lever 52 may have movement under the action of spring 55 and cam 57, causing said lever to oscillate during which movement roller 56 will have con-

tact with said cam 57. However, the projection 37 is normally located in the path of portion 54 integral with the lower end of said bell crank lever 52 and movement of the lever toward the right, Figure 1, is normally prevented by said projection. It will be clear from the previous description that said projection 37 will be located in the path of portion 54 when a sheet has been properly fed to the transfer mechanism and registered throughout its leading edge since under these circumstances air will be prevented from entering the suction openings 24 and piston 35 in the member 34 will be caused to assume an elevated position against the tension of spring 36. However, in the event a sheet is not fed to said registering mechanism, or, if the sheet fed thereto is not properly registered throughout its leading edge, air will enter those openings remaining uncovered and under these circumstances air will not be extracted from the chamber in member 34 and thus piston 35 will remain in its lowermost position, locating projection 37 within the member.

When the projection 37 is not caused to be located in the path of the bell crank lever 52 said lever will have movement toward the right under the tension of spring 55 and which movement will be in timed relation with the rotation of the impression cylinder by reason of the cam 51. Oscillation of the bell crank lever in this direction will cause the trip pin 50 to depress the trip latch 42, whereupon the driving disc 41 and the transfer mechanism will be disconnected and rotation of the transfer gripper elements for transferring a sheet to the impression cylinder will not take place but said transfer mechanism will remain at rest. It is therefore seen that by reason of the improvements of the invention the transfer mechanism does not operate to transfer a sheet to the impression cylinder when said sheet has been improperly registered or, accurately registered for only a portion of its leading edge or when a sheet has not been fed thereto at all.

The mechanism for tripping the printing couple receives its actuation from the bell crank lever 52. This mechanism consists of a lever 60 suitably journalled by the trip shaft 61 and carrying at its outer end roller 62 adapted to ride within the cam race 63 formed in the cam disc 31. The said lever 60 is therefore given oscillating motion in timed relation with the operations of the press. Suitably fixed to the trip shaft 61 is an arm 64 pivotally carrying at its outer end the dog 65 having an arcuate shape and coinciding with the arcuate shape of recess 66 formed in lever 60. Pivotally secured to one end of dog 65 at 67 is a rod 68 carrying at its upper end a pair of springs 70. Adapted to have slidable movement on rod 68 and positioned between springs 70 is a member 71 having securement to arm 72 of bell crank lever 73 suitably mounted for pivotal movement by shaft 74. The bell crank lever 73 is yieldingly forced by spring 75 in a direction to cause arm 72 to move upwardly and its oppositely directed arm 76 to move downwardly. The shaft 53 journals the latch member 77 against which arm 76 is adapted to rest when the parts are in the position shown in Figure 1. The coil spring 78 yieldingly holds the latch member 77 against portion 80 formed integral with the bell crank lever 52.

In the operation of the mechanism for tripping the impression cylinder 10 or the plate cylinder 11, as the case may be, it will be recalled that

the projection 37 is normally located in the path of the bell crank lever 52 and therefore the oscillating movement of said lever is normally restricted. However, when a sheet is not fed to the transfer mechanism, or, in the event a sheet is improperly registered, said projection will not extend in the path of portion 54 and the bell crank lever will have movement in a direction toward the right under the action of spring 55. Movement of the bell crank lever in this direction will depress the trip latch 42 and will also withdraw the latch member 77 from under arm 76, allowing the bell crank lever 73 to oscillate on shaft 74 in a counter-clockwise direction, which movement thereof will actuate rod 68, causing pivotal movement of dog 65 and location of the lower end of said dog against the lowermost shoulder 81 formed by the recess 66 in the lever 60. In other words, the said dog is oppositely positioned from that normally assumed by the same, as will be clear by comparing Figures 1 and 2. As lever 60 is caused to oscillate in an upward direction by rotation of the cam disc 31 movement will be imparted to dog 65 and to lever 64 fixed to the trip shaft 61 with the result that rocking of said trip shaft will take place and through connections from said shaft the printing couple will be tripped to prevent a printing operation.

Mechanism having connection with the shaft 61 and which is actuated upon oscillation of said shaft, as above described, to cause tripping of either the impression cylinder or the plate cylinder is not disclosed as this structure forms no part of the present invention and any conventional mechanism old and well known in the art may be employed.

It will be understood that the cam 31 has rotation so as to connect the suction openings 24 with the main suction supply tube 32 during the registering period of a sheet in contact with the registering guides 26. To accomplish this registering function of the sheet the transfer mechanism is momentarily held at rest and by reason of the detecting means and the associated parts comprising the improvements of the invention said transfer mechanism is held at rest in the event the sheet is not properly registered. It therefore follows that the transfer mechanism will also be held at rest if a sheet is not fed to the transfer mechanism at the proper time. Although the registering guides 26 perform the front registration of the sheet, the sheet retarding and aligning fingers 28 also perform a registering function. It is entirely possible to omit the registering guides 26 and rely entirely on the fingers 28 for proper registration of the entire leading edge of the sheet. However, the main function of these fingers is to slow down the sheet, which takes place during the decelerating movement of the transfer mechanism and continues until the transfer mechanism is brought to rest. During this period of deceleration of the sheet the fingers function not only to slow down the sheet but also to register the leading edge of the same and thus in the mechanism disclosed the guides 26 perform a final registering function.

In the operation of a printing press equipped with the improvements of the invention successive sheets will be fed in timed relation to the transfer mechanism, registered by the guides and transferred by said mechanism to the impression cylinder 10. As proper feeding and registration of the sheets continues it will be understood that the projection 37 will be extended into the path 75

of portion 54 to prevent oscillation of the lever 52 and actuation of the clutch means and tripping mechanism.

The improvements of the invention will have 5 operation to cause tripping of the clutch means and actuation of the trip shaft 61 only in the event a sheet is not fed to the transfer mechanism or if a sheet, although fed thereto, is not accurately registered throughout its leading edge.

10 In order to lock the lever 52 in position, as shown in Figure 1, to permit operation of the transfer mechanism, the invention provides a manually actuated rod 82 having a handle or knob 83 and which is yieldingly biased outwardly 15 by spring 84. Therefore normally the end of the rod opposite the knob is out of engagement with portion 54. Said portion is formed with an opening 85 adapted to receive the end of the rod when the same is depressed by the operator and as long 20 as said rod is held depressed the lever 52 will be locked in an inoperative position, in which position the trip latch will be operatively located to cause successive rotations of the transfer mechanism to take place.

25 What is claimed is:

1. In combination, rotary sheet transfer mechanism adapted to have movement from a position of rest for transferring a sheet to a printing member, means for registering a sheet while said transfer mechanism is at rest and before said sheet is transferred thereby, clutch means interposed between said transfer mechanism and the driving means therefor, and means having operation to actuate said clutch means permitting said transfer mechanism to remain at rest in the event a sheet is not fed to said mechanism and accurately registered by said registering means throughout its leading edge.

2. In a printing press, rotary sheet transfer mechanism for feeding sheets to a member performing an operation thereon, driving means for said transfer mechanism having accelerating motion from a position of rest whereby similar motion may be imparted to said transfer mechanism so that at the time of transfer of said sheet 45 the mechanism will have attained the surface speed of said member, clutch means interposed between the transfer mechanism and driving means therefor, and means having operation in the event a sheet is not fed to said transfer mechanism and accurately registered throughout its leading edge to actuate said clutch means disconnecting the transfer mechanism from its driving means, whereby the transfer mechanism 50 will remain at rest.

55 3. In a printing press, rotary sheet transfer mechanism for feeding sheets to a member performing an operation thereon, driving means for said transfer mechanism having accelerating motion from a position of rest whereby similar motion may be imparted to said transfer mechanism so that at the time of transfer of said sheet the mechanism will have attained the surface speed 60 of said member, registering guides for registering said sheet during the period of rest, clutch means interposed between said transfer mechanism and the driving means therefor, and means having operation in the event a sheet is not fed to said transfer mechanism and accurately registered throughout its leading edge to actuate said clutch means disconnecting the transfer mechanism from its driving means, whereby the transfer mechanism 65 will remain at rest.

70 4. In a printing press, the combination with a printing couple, of transfer mechanism adapted

to have movement from a position of rest for transferring a sheet to said printing couple, registering guides for registering the leading edge of said sheet during said period of rest and before transfer of the sheet, and means having operation to hold said transfer mechanism at rest and to trip said printing couple preventing a printing operation in the event a sheet is not fed to said transfer mechanism and accurately registered throughout its leading edge.

5 5. In a printing press, the combination with a printing couple, of transfer mechanism adapted to have movement from a position of rest for transferring a sheet to said printing couple, driving means for said mechanism having continuous 15 operation, clutch means interposed between the transfer mechanism and said driving means, and means for tripping said clutch means and substantially simultaneously tripping the printing couple, said means having operation only in the event a sheet is not fed to said transfer mechanism and properly registered during the period of rest thereof, whereby said transfer mechanism is held at rest and said printing couple is tripped to prevent a printing operation.

20 6. In a printing press, the combination with a printing couple, of transfer mechanism adapted to have movement from a position of rest for transferring a sheet to said printing couple, driving means for said mechanism having continuous 30 operation, registering guides for registering the leading edge of said sheet during said period of rest and before transfer of the sheet, clutch means interposed between the transfer mechanism and said driving means, and means for tripping said clutch means and substantially simultaneously tripping the printing couple, said means having operation only in the event a sheet is not fed to said transfer mechanism and properly registered by said registering guides, whereby 35 said transfer mechanism is held at rest and said printing couple is tripped to prevent a printing operation.

40 7. In a printing press, a printing couple, rotary sheet transfer mechanism for feeding sheets to said couple, driving means imparting periodic movement to said transfer mechanism from a position of rest, a clutch interposed between said driving means and transfer mechanism, and sheet detecting means controlling the operation of 45 said clutch, said sheet detecting means permitting tripping of said clutch to hold the transfer mechanism at rest only in the event a sheet is not fed to said mechanism and properly registered 50 during the period of rest thereof.

55 8. In a printing press, a printing couple, rotary sheet transfer mechanism for feeding sheets to said couple, driving means imparting periodic movement to said transfer mechanism from a position of rest, a clutch interposed between said driving means and transfer mechanism, and sheet detecting means controlling the operation of 60 said clutch and indirectly controlling means for tripping said printing couple to prevent a printing operation, said sheet detecting means permitting tripping of the clutch and said printing couple only in the event a sheet is not fed to said mechanism and properly registered 65 during the period of rest.

70 9. In a printing press, a printing couple, rotary sheet transfer mechanism for feeding sheets to said couple, driving means therefor, said means coming to rest during each revolution, whereby a sheet may be registered during the period of rest of the transfer mechanism and prior to being 75

- transferred thereby, a clutch interposed between said driving means and transfer mechanism, sheet detecting means for detecting the presence or absence of a sheet at the transfer mechanism during the registering period, and means controlled by the operation of said sheet detecting means for actuating said clutch. 5
10. In a printing press, a printing couple, rotary sheet transfer mechanism for feeding sheets to said couple, driving means therefor, said means coming to rest during each revolution whereby said transfer mechanism has a period of rest for registering a sheet before transferring the same, a clutch interposed between said driving means and transfer mechanism, sheet detecting means for detecting the absence of a sheet or the presence of an improperly registered sheet at said transfer mechanism during the registering period, and means having operation to trip said clutch and also said printing couple, said sheet detecting means means preventing operation of the clutch and printing couple tripping means provided a sheet has been fed to the transfer mechanism and properly registered during said 25 period of rest. 15
11. In a printing press, the combination with a printing couple of transfer mechanism including sheet retaining fingers adapted to have movement from a position of rest for transferring a sheet to said printing couple, driving means for said mechanism having continuous operation, a clutch interposed between the transfer mechanism and said driving means, means having oscillating movement in synchronism with the printing operation performed by said printing couple, said movement being effective to trip said clutch to cause the transfer mechanism to remain at rest, a trip shaft, connections operatively connecting said trip shaft with said oscillating means whereby tripping of said clutch will cause actuation of the connections to rock the trip shaft and trip said printing couple preventing a printing operation, and sheet detecting means controlling the operation of said oscillating means, said sheet detecting means causing a projection to extend into the path of said oscillating means to prevent tripping of said clutch when a sheet is fed to the transfer mechanism and properly registered during the period of rest thereof. 20 30 35 40 45
12. In a printing press, in combination, rotary sheet transfer mechanism for feeding sheets to a member performing an operation thereon, driving means for said transfer mechanism having accelerating motion from a position of rest whereby similar motion may be imparted to said transfer mechanism so that at the time of transfer of said sheet the mechanism will have attained the surface speed of said member, registering guides for registering the sheet during the period of rest and prior to transfer of the same, and clutch means responsive to the presence or absence of a sheet at said guides during their period of rest for controlling the operation of said transfer mechanism. 15 20 25
13. In a printing press, the combination with a printing couple, of transfer mechanism adapted to have movement from a position of rest for transferring a sheet to said printing couple, driving means for said mechanism having continuous operation, a clutch interposed between the transfer mechanism and said driving means, sheet detector means having operation to trip said clutch in the event a sheet is not fed to said transfer mechanism and properly registered during the period of rest thereof, and means also controlled by said sheet detector means for tripping the printing couple, which operation takes place substantially simultaneously with the tripping of the clutch. 30 35 40 45
14. In a printing press, the combination with a printing couple, of transfer mechanism adapted to have movement from a position of rest for transferring a sheet to said printing couple, driving means for said mechanism having continuous operation, a clutch located between the transfer mechanism and the said driving means, means for tripping said clutch, sheet detector means having operation to actuate the said tripping means for the clutch in the event a sheet is not fed to said transfer mechanism and properly registered during the period of rest thereof, and means receiving actuation from said clutch tripping means for tripping the printing couple, which operation takes place substantially simultaneously with the tripping of said clutch. 40 45

HENRI E. PEYREBRUNE.
